of the bolt (see Figure 5) has a head portion 25 and at the opposite end a hole 26 is provided through the round shank. A cotter pin may be passed through this hole to retain in position a blank nut 27. The bolt is prevented from coming out of the slot by the head 25 and the blank nut 27, but the bolt may be easily removed and replaced by removal of the blank nut when it is desired.

Figure 6 shows a member or bolt 28 generally 10 oval in section and having a transverse hole at each end whereby blank nuts may be retained by the employment of cotter pins.

In use the rails are laid end to end and positioned carefully on the prepared ground. The 15 stakes are then passed through slots 22 and 23 and driven firmly into the ground. While driving the stakes the bolts 24 should be received in the nests 20. The forms are then finally aligned to accurate grade and position and the bolts 24 20 are lifted from the nests and are moved down the slots to tightly engage the stake on opposite sides. The stake is very firmly held by the wedging action but whenever it becomes necessary to loosen the connection between the rail and the 25 stake a slight upward movement of the bolts will suffice. It is also of importance to bear in mind that any vibration of the form tends to lower the bolts and thus further wedge the rails and stake together and to increase the gripping action.

While I have shown a preferred embodiment of my invention, it is to be understood that various changes may be made in the details of construction without departing from the scope of my invention, as defined in the following claims.

I claim:

1. A road form and stake pocket structure comprising a rail having a vertically extending web and a horizontal base portion, a pair of spaced flanges extending perpendicular to said web and cooperating therewith to define a stake pocket, each of said flanges having a pair of downwardly converging slots extending through the walls thereof; a pair of wedging bolts respectively having opposite ends extending through similar slots to the outside of said flanges and having guided movement therein for exerting a wedging action on a stake extending upwardly through said stake pocket, and a top plate spanning and secured to the top edges of said flanges, said top plate and rail base portion having stake receiving openings for maintaining a stake in said pocket in position for wedging engagement by said bolts.

2. A road form and stake pocket structure comprising a rail having a vertically extending web and a horizontal base portion, a pair of spaced flanges extending perpendicular to said web and cooperating therewith to define a stake pocket, each of said flanges having a pair of downwardly converging slots extending through the walls thereof, and a pair of wedging bolts respectively having opposite ends extending through similar slots to the outside of said flanges and having guided movement therein for exerting a wedging action on a stake extending upwardly through said stake pocket, said structure further having vertically spaced parts with stake receiving openings therein for maintaining a stake in said pocket in position for wedging engagement by said bolts.

3. A road form and stake pocket structure comprising a rail having a vertically extending web and a pair of spaced flanges perpendicular to said web and cooperating therewith to define a stake pocket; each of said flanges having a pair of downwardly converging slots extending through the walls thereof, and a pair of wedging bolts respectively having opposite ends extending through similar slots to the outside of said flanges and having a guided movement therein for exerting a wedging action on a stake extending upwardly through said stake pocket to mount the rail on the stake whereby vibrating movement of the rail will be effective to move said wedging bolts downwardly in said slots to increase their wedging action on such stake.

4. A road form and stake pocket structure as claimed in claim 3 in which the upper ends of said slots terminate in nests in which the ends of said bolts may be received and retained against downward movement in said slots to an operative wedging position.

OTTWIN L. BRAUN.
